CLAIM

The ornamental design for a charger for portable electronic device, as shown and described.

DESCRIPTION

FIG. 1 is a front perspective view of a charger for portable electronic device showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a right elevational view thereof; and,

FIG. 7 is a left elevational view thereof.

The broken lines in the drawing figures form no part of the claimed design and depict portions of the charger for portable electronic device that form no part of the claimed design.

1 Claim, 7 Drawing Sheets
